Henry W. Nuse

UNITED STATES PATENT OFFICE.

BERNARD D'ESCAVRAC, OF NEW YORK, N. Y., ASSIGNOR TO SUERLAIN PERFUMERY CORPORATION OF NEW YORK, OF NEW YORK, N. Y., A CORPORATION OF NEW YORK.

DESIGN FOR A COMPACT CASE.

Application filed March 15, 1927. Serial No. 21,147. Term of patent 14 years.

To all whom it may concern:

Be it known that BERNARD D'ESCAVRAC, a citizen of the Republic of France, now residing at No. 33 West 55th Street, borough of Manhattan, city, county, and State of New York, has invented a new and original Design for a Compact Case, of which the following is a specification, reference being had to the accompanying drawings, forming part thereof.

Fig. 1 is a plan view of a compact case, showing my new design, and Figure 2 is an edge view of said compact case.

I claim:

The ornamental design for a compact case as shown.

BERNARD D'ESCAVRAC.
